(57) **CLAIM**

The ornamental design for a hose valve assembly for vacuum cleaning device, as shown and described.

DESCRIPTION

1. Hose valve assembly for vacuum cleaning device

1.1 : Front, top, right

1.3 : Rear

Fig. 1.1 is a front, top, right side isometric view of a hose valve assembly for vacuum cleaning device in accordance with our design; fig. 1.2 is a front elevation view thereof; fig. 1.3 is a rear elevation view thereof; fig. 1.4 is a left side elevation view thereof; fig. 1.5 is a right side elevation view thereof; fig. 1.6 is a top plan view thereof; and fig. 1.7 is a bottom plan view thereof; the broken lines illustrate portions of the hose valve assembly for vacuum cleaning device which form no part of the claimed design.
